UNITED STATES PATENT OFFICE.

SAMUEL HENRY STEWART, OF WHITEABBEY, IRELAND, ASSIGNOR OF ONE-FOURTH
TO SALT & SON LIMITED, OF BIRMINGHAM, ENGLAND.

MEANS FOR IMMOBILIZING THE LUNGS OR PORTIONS THEREOF.

Application filed December 20, 1922, Serial No. 607,938, and in Great Britain February 20, 1922.

This invention has for its object the immobilization of a portion, or the whole of a lung, or portions of the lungs, of a person, to prevent lung or pleural movements and 5 (or) to support the spinal column. In the case of a tuberculous lung, for example, the diseased organ can be restrained in its action by restraining the functioning of the associated ribs and diaphragm. This has hitherto 10 been attempted in an experimental way by means of adhesive strapping stretched on the side or portion of the body affected and according to my invention I make the process more convenient and effective by providing 15 a mechanical structure designed to allow of the required pressure being applied to restrain the part affected and to obtain the pressure by means of parts of the structure bearing on the pelvic bone while affecting 20 as little as possible the activity of the parts not affected. In apparatus according to this invention the ribs and diaphragm that it is not desired to restrain are free, the shoulder joints and hip joints are permitted to move 25 freely and the whole body is free to move from side to side, and while the apparatus can move with it the restraining pressure is maintained.

The invention will be described with reference to the accompanying drawings wherein:

Fig. 1 shows a front view of the apparatus arranged for the immobilizing of the left lung by pressure on the chest wall at the left side of the body.

Fig. 2 is a side view showing the right side of the body.

Fig. 3 is a back view.

Fig. 4 is a side view showing the left side 40 of the body.

Referring to the drawings:—

The means constituting my body or lung splint consists of two supplementary levers 1 and 2, one at the front, and one at the back of the body and supported on elbow levers 3, 3, connected to end portions 3^a, 3^a, of a member which encircles the pelvic bone on the diseased side of the body. Between the member and the pelvic bone, a suitable pad 4 is provided which may have a leg fitment for maintaining it properly in position. The points of support at which the supplementary levers 1 and 2 are connected with the upper arms 3^b, 3^b, of the elbow 55 levers allows of turning movements of the

supplementary levers and are located about the junction of the upper and middle third of the supplementary levers. The lower ends of these supplementary levers 1 and 2 have flexible adjustable connections 5, 5, to 60 the elbow levers 3, 3. By this means any movement of the spine that would impair the efficiency of the device is prevented. Suitable canvas or other belts 6 are attached to the supplementary levers and passed 65 round the affected side of the body to be tightened against the side to the required degree and fastened by means of suitable buckles, the effect being that the ribs are immobilized in the position of expiration to 70 restrain expansion of the lung. The diaphragm is also restrained.

The upper part of the chest on the affected side is held by straps 7 passing from the upper end of the posterior supplementary lever 2 over the shoulder and having attachments anteriorly to a horizontal bar 8 fixed to or forming an extension of the anterior supplementary lever 1. In addition it may be possible, when desired, to conduct similar straps over and around the body in proximity to the upper part of the opposite lung and having a similar anterior attachment. A suitable pad transmits pressure from these shoulder straps to the apex or upper part of the lung. By this means it is possible to immobilize almost entirely the whole of one lung and to restrain, if necessary, the upper part of the other. The remaining portion of the second lung is 80 found to be sufficient for functioning of the body during the process of healing of the affected parts.

The means employed for holding the double supporting levers in position comprises a pad 9 adapted to the pelvic bone on the opposite side of the body from the diseased lung. This pad 9 which may be constructed of any suitable material for comfort and efficiency, has a Y-shaped member 95 of steel encased therein as shown in dotted lines at Figs. 1 and 2. To the upper legs of the Y-shaped member an anterior strap 10 and a posterior strap 11 are attached. These straps are connected to the supporting levers 3, 3, in front of, and behind, the body at points 12 and 13 respectively, and corresponding to the point where spinal movements, independent of the pelvis, may be 100 regarded as ceasing. On the lower leg of the 105

Y-shaped member a small pivoted lever 14 is arranged and from the outer ends of this lever a padded strap 15 is conducted around the ischium. All these straps are provided 5 with suitable buckles and therefore allow of adjustment. The pad 9 can be fixed in position and yet, by virtue of the above mentioned pivoted lever 14, free movement of the leg is possible. Connections 16 and 10 17 are provided between this pad 9 and the pad 4 at the opposite pelvic bone both anteriorly and posteriorly.

All rigid parts of this structure in contact with the body are padded and covered in 15 the usual manner of surgical appliances.

A feature in connection with the hereinbefore described example of my invention is that the movements of the limbs are not impaired to any considerable degree. It 20 also should be noted that no pressure is applied to the abdomen or other region likely to impair to any considerable degree movements of what may be regarded as the sound lung. Another advantage of this arrangement is that by compressing the ribs and the abdomen on the side of the affected lung, diaphragmatic movement will be considerably reduced.

Suitable modifications of the invention 30 may be adopted to effect the mechanical immobilization of the lung or portion thereof and the foregoing are merely recited as examples of suitable apparatus.

Having now fully described my invention 35 what I claim and desire to secure by Letters Patent is:—

1. A mechanical apparatus for attachment to the human body to restrain ribs and lung and pleural movements on one side of the 40 body, comprising, in combination, levers at the back and front of the body; means for mounting said levers so that they act through a fulcrum located about a point which may be regarded as that where spinal movement independent of the pelvis ceases; flexible straps attached to the levers and adapted to 45 pass round the affected side of the body and non-rigid straps for producing the required restraining pressure acting mainly upon the pelvic bone and connected to the levers at said point whereby the upper part of the

apparatus can move with the body about the said point while the restraining pressure is maintained, and means for stabilizing said non-rigid straps. 55

2. A mechanical apparatus for attachment to the human body to restrain lung or pleural movements on one side of the body, comprising two supplementary levers one at the front and the other at the back 60 of the body, flexible straps attached to the said levers and embracing the affected side of the body, elbow levers fulcrumed to said supplementary levers, a member connected to the said elbow levers and encircling the 65 pelvic bone on the diseased side of the body, straps connected to the elbow levers at points corresponding to the point where spinal movement independent of the pelvis ceases and connected also to a member located on 70 the opposite pelvic bone, the arrangement being such as to leave free the ribs and diaphragm on the healthy side of the body.

3. A mechanical apparatus for attachment to the human body to restrain lung or pleural movements on one side of the body, comprising two supplementary levers one at the front and the other at the back of the body, flexible straps attached to the said levers and embracing the affected side of the body, elbow levers fulcrumed to said supplementary levers at about the junction of the upper and middle thirds of said supplementary levers, a member connected to the 75 lower ends of said elbow levers and encircling the pelvic bone on the diseased side of the body, flexible adjustable connections between said elbow levers and the lower ends of said supplementary levers, adjustable straps connected to the elbow levers at points 80 corresponding to the point where spinal movement independent of the pelvis ceases and connected also to a Y-shaped member embodied in a pad located on the opposite 85 pelvic bone, the arrangement being such that the ribs and diaphragm on the healthy side of the body are left free and that the restraining force is exerted from the pelvic bone. 90

In testimony whereof I affix my signature.

SAMUEL HENRY STEWART.
